UNITED STATES PATENT OFFICE.

ANTHONY ELTON DAVIS, OF PHILADELPHIA, PENNSYLVANIA.

CONCRETE-INSERT.

1,241,827.

Specification of Letters Patent.

Patented Oct. 2, 1917.

Application filed March 2, 1915. Serial No. 11,631.

To all whom it may concern:

Be it known that I, ANTHONY ELTON DAVIS, a citizen of the United States, residing in the city and county of Philadelphia, State of Pennsylvania, have invented a new and useful Concrete-Insert, of which the following is a specification.

My present invention relates to concrete inserts, which are a type of socket or hanger designed to be embedded in concrete ceilings, walls, or similar constructions, during their construction, so that at any time after the construction is completed, brackets, hangers, pipes, or any other desired construction may be supported by such concrete inserts, without injury to the concrete construction.

With the above in view, my invention consists of a concrete insert of the character stated, and wherein provision is made for preventing the disarrangement of the concrete insert with respect to the concrete, and wherein means are provided for covering the lower end of the threaded aperture, which is adapted to receive a fastening device.

It further consists of a novel insert provided with anchoring devices, and having its body portion provided with upwardly directed strengthening ribs and with a chamber or recess located above the threaded portion of the aperture, so that the breaking of the taps, used to cut the thread in the aperture, is practically eliminated, due to the provision of such chamber.

It further consists of a novel construction of an insert having a threaded aperture therein, and novel means for closing the outer end of such aperture, to prevent accumulation of foreign material therein and the rusting and disintegration of the threads.

Other novel features of construction and advantage will hereinafter more clearly appear in the detailed description.

For the purpose of illustrating my invention, I have shown herein a typical embodiment thereof which will give in practice satisfactory and reliable results, although, of course, it is to be understood that the various instrumentalities of which my invention consists can be variously arranged and organized and that my invention is not limited to the precise arrangement and organization of these instrumentalities, as herein shown and described.

Figure 1 represents a front elevation, partly in section, of a concrete insert embodying my invention, and the concrete construction in which it is placed.

Fig. 2 represents an end elevation of the concrete insert, showing, in addition, the manner in which it is connected, with a temporary support.

Fig. 3 represents a perspective view of the insert in detached position. 65

Fig. 4 represents a bottom plan view.

Fig. 5 represents a perspective view of a closure employed in conjunction with the insert.

Similar numerals of reference indicate 70 corresponding parts in the figures.

Referring to the drawings.—

1 designates the body portion of a concrete insert embodying my invention, and in the present instance, the upper portion 75 thereof is shown as having a substantially cylindrical contour, while the lower portion 2 is of reduced diameter and provided with reinforcing ribs 3, which may have any desired formation and extend in any desired 80 direction, but for purposes of illustration, I have preferred to show them as being upwardly directed from the angularly arranged base or foot members or flanges 4, and any desired number of these base 85 flanges may be provided with the recesses or notches 5, which are illustrated as being substantially V-shaped. The purpose of these recesses 5 is to provide for securing the insert in position on a temporary support or centering 6, (see Fig. 2), by means of fastening devices 7. 8 designates an aperture extending into the body portion of the insert, which is interiorly threaded, and opens into an enlarged inner chamber 9 95 of greater diameter than the aperture 8, so that when the threads are being tapped, the provision of the chamber 9 will eliminate, in a large measure, the breaking of the taps, which would otherwise take place if the 100 chamber 9 were omitted. The bottom or end wall of the insert is recessed at an acute angle, as at 10, so that a polygonal shaped recess is formed to receive a polygonal shaped closure 11 having the inclined outer 105 wall 12, so that said closure will fit such recess, as seen in Fig. 1, and close the outer end of the aperture 8. In order to provide for the insertion and removal of the closure 11, one of the foot flanges 4 is provided 110

with an inclined face 13, (see Figs. 1 and 4). Certain of the foot flanges 4 are connected at their inner ends by a web 14, which is removed in proximity to the foot flange 4 which has the upwardly inclined wall 13, in order to provide for the ready insertion or removal of the closure 11.

15 designates arms which diverge from the body portion 1 and terminate in outwardly extending parallelly arranged portions 16. The side walls of the arms 15 converge toward their outer ends, as indicated at 17 in Fig. 2, and the end portion 16 are provided with the outwardly extending lugs 18, which serve as anchoring elements to prevent displacement of the insert with respect to the concrete.

In practice, the concrete is reinforced by bars or deformed rods of any desired or conventional shape, and in Fig. 1, I have shown a deformed rod 19, it being understood that the socket may or may not embrace the reinforcing members employed.

Owing to the employment of the ribs 3 or 25 their equivalent, the body portion of the socket is firmly interlocked in the concrete and the torsional strain on the socket, when the fastening devices are being connected therewith, is thereby decreased.

30 The closure 11 is preferably constructed of a waterproof or water resisting material, such as cork, cardboard, or other suitable material, and this closure is adapted to be located in place by moving the closure in 35 a lateral direction to engage the recess, and as soon as the closure is positioned, it will be held in place and prevented from accidental displacement and will not be effected by the moisture in the concrete, so that 40 such closure will stay in position for an indefinite period of time. The closure also prevents the moisture in the concrete from affecting the threads on the wall of the aperture 8. By the provision of the V-shaped 45 notches in the foot flanges 4, the fastening devices will accurately position the socket or insert with respect to the centering.

It will now be apparent that I have devised a novel and useful concrete insert, 50 which embodies the features of advantage enumerated as desirable in the statement of the invention and the above description, and while I have, in the present instance, shown and described a preferred embodiment 55 thereof which will give in practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

65 1. A device of the character stated for

embedment in a concrete construction, comprising a body portion and arms extending outwardly therefrom, said body portion having an aperture opening through an end thereof and terminating inwardly in a chamber of greater diameter than the diameter of said aperture, the walls of said aperture being threaded, said body portion having a laterally extending recess near the open end of said aperture, means to secure 70 said body portion in position and a closure independent of said body securing means and adapted to engage said recess and to be inserted thereinto by movement in a lateral direction.

2. A device of the character stated for embedment in a concrete construction, comprising a body portion, arms extending outwardly therefrom, and angularly arranged base flanges at its opposite end and provided with means to receive fastening devices, said body portion having an aperture opening thereinto and terminating inwardly in a chamber of greater diameter than the diameter of said aperture, the walls of said aperture being threaded, said body portion having a laterally directed recess surrounding said aperture, the walls of said recess forming an acute angle, and a closure shaped 85 to engage said recess and adapted to be 90 laterally inserted therein.

3. A device of the character stated for embedment in a concrete construction, comprising a body portion having angularly disposed base flanges at one end, certain of said flanges having V-shaped notches therein, said body portion having outwardly diverging arms extending from its opposite end, said arms terminating in parallelly arranged extensions increasing in width at their outer ends, said body portion having an aperture opening thereinto and terminating in a chamber of greater diameter than the diameter of the aperture, the outer face of said body portion having a portion of reduced diameter provided with ribs to interlock with the concrete, said body portion having a recess around said aperture near its outer end, said recess having a side wall thereof cut away, and a closure shaped to 100 interlock with said recess and having its under face substantially flush with the under face of said base flanges.

4. A device of the character stated for embedment in a concrete construction, comprising a body portion having angularly disposed base flanges at one end, certain of said flanges having V-shaped notches therein, said body portion having outwardly diverging arms extending from its opposite end, 105 said arms terminating in parallelly arranged extensions increasing in width at their outer ends, said body portion having an aperture opening thereinto and terminating in a chamber of greater diameter than 110
